UNITED STATES PATENT OFFICE.

MAX JANICKE, OF HALLE-ON-THE-SAALE, GERMANY.

FEED DEVICE FOR THE MANDRELS OF MACHINE TOOLS OF ALL KINDS.

1,400,072.

Specification of Letters Patent. Patented Dec. 13, 1921.

Application filed April 18, 1916. Serial No. 92,024.

(GRANTED UNDER THE PROVISIONS OF THE ACT OF MARCH 3, 1921, 41 STAT. L., 1313.)

To all whom it may concern:

Be it known that I, MAX JÄNICKE, a subject of the German Emperor, and residing at No. 13 Aeussere Delitsscherstrasse, Halle-on-the-Saale, Germany, manufacturer, have invented certain new and useful Improvements in a Feed Device for the Mandrels of Machine-Tools of All Kinds, (for which I have filed application in Germany, No. 10 16,925, filed June 29, 1914; Austria, filed June 26, 1915; Hungary, filed June 26, 1915, and France, filed July 8, 1915,) of which the following is a specification.

The present invention relates to a feed 15 arrangement which may be applied to machines for various purposes, in which a tool or a piece of work has to be fed.

In this drawing a constructional form of the device is exemplified.

20 Figure 1 is a section on the line A—B in Fig. 2.

Fig. 2 is a section on the line C—D in Fig. 1.

The mandrel *a* carrying the tool or the 25 work and driven by any suitable means (not shown) is threaded along a considerable part of its length and is screwed with this thread into a nut *b*, which has on the rim of a rearwardly extending flange *c* an internal ratchet gear *d*. Into the teeth of said 30 internal gear *d* engages a pawl *e*, which is fitted loose on a pivot *f*. This pivot is disposed in a lever *g*, which has at its front end a nose *h*. This lever *g* is fitted at its 35 rear end by means of a pin *i* revolvably to a disk *k*, the rear face *l* of which faces the front face *m* of the nut *b*, and which has a bore to allow of the mandrel passing through it. Between the disk *k* and the nut is disposed 40 in a corresponding recess a clutch cone *n*, which engages with a feather or key *o* in a corresponding longitudinal groove in the mandrel, and must therefore revolve continuously with said mandrel, but allows of a 45 relative longitudinal displacement. The pawl *e* is under action of a spring *p*, which tends to hold the pawl in engagement with the said internal gear *d*. At the rear end of the pawl *e* is provided a tooth *q*, which 50 likewise engages into the internal gear *d*. At the side an abutment *r* is disposed in

such a manner, that when the disk *k* is revolved, the nose *h* of the lever *g* will strike against the said abutment *r*.

The operation of the device is as follows: 55 When the mandrel is rotated either manually or mechanically in one or the other sense, as indicated in the drawing in Fig. 2, in the clockwise direction, it will carry with it the nut *b* by friction as long as such rotation of said nut is not prevented. Owing to the engagement between the teeth *d* and the ratchet member *e*, the nut carries with it the member *k* which has thereon the member or lever *g*. Now at one side of the member *k* is a fixed abutment *r* two faces of which are inclined to the horizontal and which project into the path of the end *h* of the member *g*. During the first rotation of the arm *g*, the nose or end thereof *h* 60 strikes against the abutment *r* whereby the rotation of the member *k*, and in consequence of the ratchet engagement between it and the nut *b*, also the further rotation of the nut is temporarily prevented. In consequence thereof the spindle *a* will, owing to its continued rotation, screw itself with its thread forward in the nut *b* and will thereby 65 approach the tool to the work at a relatively high speed. However, as soon as the tool carrying mandrel has reached its operative position, its forward movement is resisted by the pressure of the tool against the work and it now exerts an axial pressure against the nut *b* in the reversed direction to the 70 previous movement of the spindle *a*, so that the nut *b* forces the cone *n* tightly into the member *k* and thereby couples the latter to the spindle *a*. In consequence thereof, the member *k* is now strongly urged to turn in 75 the clockwise direction with the spindle *a* as viewed in Fig. 2. This movement of the member *k* is resisted by the abutment *r* so as to turn the flange *c* and nut *b* in the contra-clockwise direction with relation to 80 the member *k* owing to the engagement between the ratchet *e* and the teeth *d*. This relative motion, however, compresses the spring *p* and permits the lever *g* to swing inwardly away from the abutment *r* and 85 thereby slips off the abutment, the spring *p* expanding again as soon as the nose *h* slips 90 100

past the abutment throwing the ratchet *e* forward on the teeth *d* in the clockwise direction and bringing the lever *d* again into the same relative position as shown as in Fig. 2. However, it will be seen that as the member or nut *b* is thus positively screwed in the contra-clockwise direction with relation to the spindle *a*, the spindle is positively screwed forward in the direction of the arrow in Fig. 1 so that the tool at the forward end of the spindle is thrust positively into the metal being worked upon. This forward thrust, of course, lasts only during a small portion of the revolution of the spindle, the spindle remaining stationary as to longitudinal movement until the nose *h* comes around again and strikes the abutment *r*. The operation just described is then repeated the nose *h* striking and slipping off the abutment *r* once in each revolution and consequently giving the spindle *a* a forward thrust once in each revolution in order to feed the tool into the work at a relatively slow speed. Now when the tool has been advanced far enough with relation to the work, the rotation of the mandrel is reversed, and the nose *h* strikes the abutment *r* at the opposite end of the nose whereby the tooth *q* is forced against the teeth *d* and there being no way for the lever *g* to slip or for the member *e* to slide owing to the relative inclination of the contacting surfaces of the teeth *q* and the teeth *d*, the nut *b* is positively locked and the spindle *a* moves rapidly backward. From the foregoing it will be seen that I have provided an arrangement whereby the tool will be rapidly advanced into cutting position and removed from cutting position when required, but will be fed forward

slowly during the actual progress of the work.

Having thus described my invention, I claim:

1. A feed device for a mandrel of machine tools comprising in combination a nut, a mandrel having threaded engagement with said nut, and means for continuously preventing the rotation of said nut during the idle travel of the mandrel, and means whereby said nut is arrested intermittently upon resistance being applied to the mandrel during its feeding motion.

2. Feed device for the mandrel of machine tools of all kinds, especially drilling machines, comprising a nut, the mandrel screwing with a thread in said nut, said nut fitted with an internal ratchet gear, a double ended pawl, adapted to engage with either end in said internal gear, a lever having a pin on which said pawl is fitted loose, a disk member having a bore through which said mandrel passes, said lever being pivoted to said disk member, on said lever a nose, an abutment disposed at one side and adapted to engage with said nose and thereby arrest said nut, recesses in said disk member and said nut, in said recesses a clutch cone axially displaceable on, but positively revolvable with said mandrel, and adapted to be forced by said nut into said disk member on a resistance by the work being reached.

In testimony whereof I affix my signature in presence of two witnesses.

MAX JÄNICKE.

Witnesses:

RUDOLPH FRICKE,
MARTA MALAPP.
